UNITED STATES PATENT OFFICE

PHILIP A. REUTTER, OF WATERBURY, CONNECTICUT, ASSIGNOR TO SCOVILL MANUFACTURING COMPANY, OF WATERBURY, CONNECTICUT, A CORPORATION OF CONNECTICUT

VANITY BOX

Application filed October 9, 1928. Serial No. 311,277.

This invention relates to improvements in vanity boxes or cases, and particularly to an improved means for holding a cosmetic compact or other toilet article in the case.

5 These small boxes or cases which have now become known in the art as vanity cases, are usually made of light metal and are arranged to carry cosmetic, such as rouge or powder compacts, and a mirror. In certain of these 10 vanity cases, it is desirable that the powder compact be securely held in the case, so that it will not become accidentally displaced during use, and it is further desirable that the compact be so held that it can be readily removed from the case, so that a fresh or new compact can be inserted therein.

It is the special object of the present invention to provide an improved compact holding means for locking the compact in place, 20 but which may be readily manipulated by a suitable tool, such as a pin, to free the compact, so that it can be removed from the case for renewal.

A further object of the invention is to provide such a compact holding device which shall be simply formed, and, therefore, cheap and economical to manufacture, and which can be easily and quickly positioned in the case so as to effect ready assembly.

30 A further object of the invention is to utilize the compact holding device as part of a hinged member for pivotally uniting the body of the case with a cover.

With these and other objects not specifically referred to in view, the invention consists in certain novel parts, arrangements and combinations which will be described in connection with the accompanying drawings and the novel features pointed out in the claims hereunto annexed.

40 Referring now to said drawings:

Fig. 1 is an edge view of a closed vanity box or case with which the invention may be used.

45 Fig. 2 is a face view of the case shown in Fig. 1, the parts being shown open.

Fig. 3 is a central sectional view, taken on the line 3—3 of Fig. 1.

50 Fig. 4 is a detail sectional view, taken on line 4—4 of Fig. 1; and

Fig. 5 is a plan view of one part of the compact holder.

Referring now to these drawings—

The invention is designed for and is capable of use with vanity boxes or cases of widely varying forms. The box or case selected to illustrate the invention, however, is a thin edged box of light metal, including a body 1 to which is pivotally attached a cover 2 by a hinge 3 hereinafter referred to. In the particular case illustrated, the body 1 is of shallow dish-shape, and is capacitated to hold a cosmetic shown in the form of a powder-cake 4, molded into a tray 5 having a narrow peripheral flange 6. The cover 2, in the case 65 illustrated, is also of shallow dish-shape, being of slightly less diameter than the body 1, and this cover is also capacitated to hold a toilet article, shown as a mirror 7.

In accordance with the invention, a compact holding device of simple form is shown for removably holding the compact in place. While the specific embodiment of this compact holding device may be somewhat varied, in the particular construction shown, such 75 compact holding device comprises two similar pieces of resilient metal, shown in the form of a wire, these two pieces of wire being marked 8, 9. These two wire holders are held in place in the box by the spring of the 80 metal, being sprung into a bead 10, terminating in an inturned flange 11 forming the top of the body 1. These two wire holders are, furthermore, dimensioned, when sprung into place, to occupy the entire circumference of 85 the bead; the ends of these wires abutting, as indicated at 12, in Fig. 2. Each of these wires and at opposite ends thereof, is provided with a projection arranged to extend in over the compact, such projections being marked 13, 90 14. Such projections are easily produced by stamping or swaging the metal of the wire. By inserting a pin or like tool behind the wire, one of these wires, as 9, may be readily removed from the box, so as to release the 95 compact, and as readily replaced after a new compact has been put in position in the case.

While the hinged construction for pivotally uniting the body and cover of the box may be of any desired form, in accordance with 100

the present invention, one of the compact holding wires is utilized for this purpose, the wire 8, in the particular instance illustrated, being so used. Cooperating with this wire to form the hinge, is a hinged knuckle 15 formed by turning over a projection formed on the cover of the box, the clear end of the wire 8 being passed through the knuckle so formed and hinging the cover and the body together. This hinged knuckle is dimensioned so as to form, in effect, a continuation of the bead, thus producing a neat appearing box, the knuckle seating in a recess, indicated at 16, in Fig. 2.

15 The mirror 7 may be held in position in the cover in any suitable manner, as by means of a bezel 17 sprung into place in the cover 2.

The cover and the back may be held together by means of a spring latch, indicated 20 at 18, conveniently located in the cover of the box, the locking member of this latch engaging under the flange 11 of the body at a point opposite the hinge. If desired, or necessary, the wire 9 may be cut away, as indicated at 19, in Fig. 4, to permit this engagement of the spring catch and the flange.

It will be observed that with the construction shown and described, a very simple and at the same time effective construction has 30 been provided for holding a compact in place, and one which is cheap to make and easy to assemble. While the compact holding projections are shown as formed at the ends of the wire, it will be understood that they can be formed at other points thereof. It will 35 also be understood that spring metal other than round wire may be employed, if desired, and that the compacting holding devices may be used in a large variety of vanity cases or boxes. The invention is, therefore, 40 not to be limited to the case or to the exact construction of the holding devices shown and described.

What is claimed is:

45 1. In a vanity case, the combination of metal body and cover members, one of these parts having a hinged knuckle formed by turning over the metal of the part, and the other having an edge opening into which the 50 knuckle fits, and compact holding means including two similar wires each of which has a lateral projection arranged to overlie a compact in one of the members, and the other of which forms the pintle, one of the members 55 having a flange under which the wires are held, the wires extending completely around the member and the ends of the wires abutting.

60 2. In a vanity case, the combination of body and cover members, a compact, positioned in one of the members, and a compact holding device including two similar strips of spring metal each of which has a 65 lateral holding projection, the strips being

held in the case by the spring of the metal and with their ends in abutting relation.

3. In a vanity case, the combination of body and cover members, a compact positioned in one of the members, and a compact holding device including a pair of similar spring wires each of which is formed with a compact holding projection, the ends of said wires abutting when in position in the case, and one of the wires forming a pintle for hingedly connecting the body and the cover.

4. In a vanity case, the combination of body and cover members, a compact positioned in one of the members, and a compact holding device including two similar spring wires each of which has its end swaged to form a lateral holding projection, the wires being held in the case by the spring of the metal and with their ends abutting.

In testimony whereof, I have hereunto set my hand.

PHILIP A. REUTTER.
